UNITED STATES PATENT OFFICE.

JAMES H. DEAN, OF LUDINGTON, MICHIGAN, ASSIGNOR TO NORTHWESTERN EXPANDED METAL COMPANY, OF CHICAGO, ILLINOIS, A CORPORATION OF ILLINOIS.

MANUFACTURE OF EXPANDED METAL.

Application filed July 26, 1926. Serial No. 124,799.

The present invention relates to the manufacture of expanded sheet-metal and seeks to provide an improved method and apparatus for making metal lath having expanded diamond mesh panels extending longitudinally of the sheet between unexpanded strips or ribs. Heretofore, in the manufacture of this type of expanded metal by passing previously slotted sheets through suitable rolls and guides, it has been considered necessary, in order to expand the panels by bending and without materially stretching the strands, to spread or separate the unslotted strips and deflect each of the panels from one fixed plane to another. Usually the rows of strands and integral connecting bonds in the slotted panels of the sheet are oppositely inclined in adjacent panels and the expansion is effected by deflecting the strips or some of them transversely of the plane of the sheet to spread the strips apart and bring the sheet into troughed or corrugated form with the expanded panels disposed in transversely and oppositely inclined planes. After the slotted panels are thus expanded the sheet is flattened by laterally spreading the unslotted strips.

In accordance with the present invention the sheets are slotted in relatively narrow panels and the expansion is effected, preferably without separating or increasing the distances between the central portions of the unslotted strips, by progressively turning or twisting the portions of the strips at the sides of each panel longitudinally; and, in accordance with the preferred practice of the invention, by forming the strips into deep ribs substantially V-shaped in cross-section and projecting alternately in opposite directions from the general plane of the sheet, the ribbing of the strips being so effected that the sides of the ribs are inclined in the same direction as the bonds and strands of the adjacent expanded panels. Preferably, the ribs are then flattened and laterally spread or deflected to increase the widths of the strips and of the sheet, and the strips are provided with central stiffening beads or shallow ribs.

The distinctive features of the invention are hereinafter more fully set forth and particularly pointed out in the appended claims. In the accompanying drawings, which illustrate the preferred form of apparatus employed,

Fig. 1 is a plan view of the rolls and guides;

Fig. 2 is an elevation of the rolls and guides;

Figs. 3, 4, 5, 6, 7 and 8 are detail views illustrating the operation of the rolls for feeding the sheet and for deflecting or shaping the unslotted strips, the sheet operated upon being shown in sections taken on lines at right angles to the direction of its movement;

Figs. 9 and 10 are cross-sections illustrating the preferred forms of the guides for the unslotted strips;

Fig. 11 is a plan view of a portion of the slotted sheet; and

Fig. 12 is a plan view of a portion of the finished sheet.

The apparatus employed, in the preferred form shown, comprises a pair of feed rolls 1, three pairs of rolls 2, 3 and 4 which are arranged to engage the strips and form the same into deep V-shaped ribs alternately projecting in opposite directions, two pairs of rolls 5 and 6 for flattening and centrally beading the deeply ribbed strips, a pair of feeding and setting rolls 7 and a set of leveling rolls 8. The rolls 2, 3, 4, 5, 6 and 7 are made up of discs and spacing collars mounted on central cores or shafts and the discs of each pair of rolls are provided with correspondingly shaped ribs and grooves for engaging and shaping the unslotted strips of the sheets and for feeding the sheets. Parallel guides 9 for the unslotted strips or ribs of the sheets are provided between the pairs of rolls 1, 2, 3, 4 and 5 and divergent guides 10 are provided between the rolls 5 and 6 and the rolls 6 and 7. The rolls and guides are mounted in suitable frame work and the rolls are driven by suitable gearing at the same peripheral speed. The frame work and drive gearing are not shown but may be similar to those shown in the prior application of G. W. Baker and James H. Dean filed in the United States Patent Office March 1, 1926, Serial No. 91,564.

The metal sheets are first cut or slashed, preferably by means of roller dies such as those shown in the application for patent of James H. Dean filed in the United States Patent Office August 14, 1925, Serial No. 50,176, to provide rows of inclined slits (see Fig. 11) so as to form strands α between the rows of slits with integral connecting bonds 110

b between the slits of each row, such bonds being staggered, that is to say, the bonds of each row of slits are opposite the slits in the adjacent rows. Preferably as shown the 5 slotted panels are relatively quite narrow and are of substantially the same width as the unslotted strips. The slotted panels and the unslotted strips extend longitudinally of the sheet and the bonds and strands of adjacent 10 panels are oppositely inclined. The slitting of the sheets slightly deflects portions of the strands and bonds from the original plane of the sheet and preferably the feed rolls 1 at the front of the machine which initially 15 engage the sheets are so adjusted that they flatten or partially flatten the bonds and strands. These rolls as shown are preferably solid.

The discs or roller dies *c* and *c'* of the 20 rolls 2, 3 and 4 are provided with V-shaped grooves and corresponding V-shaped peripheries and serve, as shown in Figs. 3, 4 and 5, to progressively, and preferably in three 25 stages, form the unslotted strips of the sheet into deep V-shaped ribs with the marginal and odd numbered ribs projecting in one direction from the plane of the sheet and the even numbered ribs in the opposite direction. In this way the portions of the strips 30 at the sides of each panel are deflected in opposite directions from the general plane of the sheet and are turned or twisted longitudinally to thereby gradually draw apart the side edges of each panel and expand the 35 same. It is noted that in effecting this expansion the bonds and strands of adjacent panels are oppositely inclined and that the sides of each of the V-shaped ribs are inclined in the same direction as the bonds and 40 strands of the panels into which they merge. That is to say, in effecting the expansion of the panels, the portions of the strips at the sides of each panel and the bonds and strands of such panel are turned from the original 45 plane of the sheet so that they are inclined in the same direction and also at substantially the same angle of inclination. It is further noted that in effecting the expansion 50 of the narrow panels the lateral spacing of the central portions of the unslotted strips is not changed. That is to say, the lateral spacing of the central portions of the strips is maintained uniform and the strips are maintained parallel to one another, to the 55 path of movement of the sheet and to the original plane of the sheet. It is also noted that preferably as shown, the rolls 3, 4 and 60 5 are so arranged that the expansion of the panels is effected while maintaining the panels substantially in a common plane and substantially in the original plane of the sheet and without troughing or corrugating the sheet to bring the panels into oppositely and transversely inclined planes as in the 65 prior practice. Nevertheless, as in the prior

practice, the expansion is effected by bending and without materially stretching the strands.

To be sure that there is no material stretching of the strands it is necessary that 70 a slight relative longitudinal movement be permitted between adjacent strands. For this reason the discs *c* of the rolls 2, 3 and 4 which engage the marginal and odd numbered strips of these sheets are arranged to 75 grip the strips with sufficient pressure to feed the sheets but the discs *c'* which engage the even numbered strips have a slight additional clearance so that they merely serve to shape the even numbered strips and engage 80 them sufficiently loosely to permit the strips to move longitudinally to a slight extent relatively to the odd numbered strips. The parallel guides 9 leading from the rolls 2, 3 and 4 are provided with passes for the guides 85 corresponding in shape to those of the respective pairs of rolls. The receiving ends of these guides are arranged closely adjacent the rows to properly strip the sheets from the rolls.

After the expansion has been effected by deflecting or shaping the unslotted strips as described, the latter are preferably flattened and laterally spread to increase the widths of the strips and of the sheets. For this purpose the pairs of rolls 5 and 6 and the deflecting guides 10 are provided. The shaping discs or dies of the rolls 5 partially flatten the strips and those of the rolls 6 further flatten and preferably form the central portions of the strips into stiffening beads or shallow ribs. The flattening of the strips tends to somewhat contract the widths of the expanded panels but any such contraction is compensated for by the divergent guides 10. Indeed, if desired, the divergent guides 10 may be arranged to somewhat additionally expand the panels. Preferably as shown in Fig. 10, one of the members of each of the guides is grooved to receive the corresponding ribbed strip and the other member of the guide while not ribbed serves to hold the strip in position in such groove. The ribs and grooves of the rolls 7 correspond in shape to those of the rolls 6 and these rolls 110 serve to withdraw the sheets from the divergent deflecting guides 10 and deliver the sheets to the flattening rolls 8. The rolls 7 and 8 serve to straighten the sheets and set the expansion. Preferably also the collars 115 *d* of the rollers 7 are of such size that, as indicated in Fig. 8, the strands and bonds are flattened; that is to say, are twisted or pressed toward the plane of the sheet.

Changes may be made in the details set 120 forth without departure from the scope of the invention as defined in the claims.

I claim as my invention:

1. The method of expanding metal sheets 125 having alternate slotted panels and unslotted

strips which consists in progressively deflecting the portions of the strips at the sides of each panel in opposite directions from the general plane of the sheet while maintaining the central portions of the strips at substantially uniform distances apart.

2. The method of expanding metal sheets having staggered rows of inclined slits arranged in panels, which consists in expanding the panels by continuously advancing each sheet and progressively twisting the portions of the unslotted strips at the sides of each panel in opposite directions from the general plane of the sheet while maintaining the central portion of the strips parallel to one another and to the direction of movement of the sheet.

3. The method of expanding metal sheets having staggered rows of inclined slits arranged in panels, which consists in expanding the panels by continuously advancing each sheet and progressively twisting the portions of the unslotted strips at the sides of each panel in opposite directions from the general plane of the sheet while maintaining the central portion of the strips parallel to one another and to the direction of movement of the sheet, and then twisting the strips back toward the general plane of the sheet and simultaneously deflecting the same in such plane.

4. The method of expanding metal sheets having alternate slotted panels and unslotted strips which consists in effecting the expansion of the slotted panels by forming the strips at the sides of each panel into deep ribs projecting in opposite directions from the general plane of the sheet.

5. The method of expanding metal sheets having inclined rows of staggered slits arranged in panels with unslotted strips at the sides of each panel and with the slits of adjacent panels oppositely inclined, which consists in effecting the expansion of the slotted panels by progressively deflecting the unslotted strips alternately in opposite direction from the general plane of the sheet to form deep ribs parallel to each other and to the direction of movement of the sheet.

6. The method of expanding metal sheets having inclined rows of staggered slits arranged in panels between unslotted strips with the slits of adjacent panels oppositely inclined, which consists in progressively deflecting the unslotted strips alternately in opposite direction from the general plane of the sheet to form deep ribs parallel to each other and to the direction of movement of the sheet, then flattening and laterally spreading the ribbed strips.

7. The method of expanding metal sheets having inclined rows of staggered slits arranged in panels between unslotted strips with the slits of adjacent panels oppositely inclined, which consists in progressively de-

flecting the unslotted strips alternately in opposite direction from the general plane of the sheet to form deep ribs parallel to each other and to the direction of movement of the sheet, then flattening, laterally spreading and centrally beading the ribbed strips.

8. The method of forming expanded metal lath which consists in slitting the sheets in panels and between unslotted strips to form rows of strands and bonds with the rows in adjacent panels oppositely inclined, continuously advancing the sheet and effecting the expansion of the slotted panels by progressively forming the unslotted strips into substantially V-shaped ribs projecting alternately in opposite directions from the general plane of the sheet with the sides of the ribs inclined in the same direction as the bonds and strands of the adjacent panels.

9. The method of forming expanded metal lath which consists in slitting the sheets in panels and between unslotted strips to form rows of strands and bonds lying substantially in the planes of the sheets with the rows in adjacent panels oppositely inclined and then expanding the panels while maintaining the same substantially in the original plane of the sheet, by progressively forming the unslotted strips into substantially V-shaped ribs.

10. The method of forming expanded metal lath which consists in slitting the sheets in panels and between unslotted strips to form rows of strands and bonds with the rows in adjacent panels oppositely inclined and then expanding the panels while maintaining the same substantially parallel to the original plane of the sheet, by progressively forming the unslotted strips into substantially parallel V-shaped ribs with the sides thereof inclined in the same direction as the bonds of the adjacent panels.

11. The method of forming expanded metal lath which consists in slitting the sheets in panels and between unslotted strips to form rows of strands and bonds with the rows in adjacent panels oppositely inclined, expanding the panels while maintaining the same substantially parallel to the original plane of the sheet, by progressively forming the unslotted strips into substantially parallel V-shaped ribs with the sides thereof inclined in the same direction as the bonds of the adjacent panels, then flattening and laterally spreading the strips.

12. The method of forming expanded metal lath which consists in slitting the sheets in panels and between unslotted strips to form rows of strands and bonds with the rows in adjacent panels oppositely inclined, expanding the panels while maintaining the same substantially parallel to the original plane of the sheet, by progressively forming the unslotted strips into substantially parallel V-shaped ribs with the sides thereof in-

clined in the same direction as the bonds of the adjacent panels, then flattening, laterally spreading and centrally beading the strips and flattening the strands and bonds of the 5 expanded panels.

13. The method of forming expanded sheet metal which consists in slitting the sheets in panels and between unslotted strips to form rows of strands and staggered bonds 10 with the rows oppositely inclined in adjacent panels, expanding the slotted panels by bending and without stretching the strands, by continuously advancing the sheet in a direction parallel to its plane, and progressively 15 forming the unslotted strips into substantially V-shaped ribs projecting alternately in opposite direction from the general plane of the sheet and permitting a slight relative longitudinal movement between alternate strips.
14. The method of forming expanded metal sheets which consists in slitting the sheets in relatively narrow panels and between unslotted strips to form rows of strands and integral staggered bonds oppositely inclined 20 in adjacent panels and expanding the panels by passing the sheets through roller dies to progressively deflect the portion of the strips at the sides of each panel in opposite direction from the plane of such panel while 25 maintaining the central portion of the strips uniformly spaced and parallel to the original plane of the sheet.

15. Apparatus for expanding metal sheets having alternate slotted panels and unslotted 30 strips, comprising feeding and forming rolls for engaging the strips and continuously advancing the sheet and for deflecting the portions of the strips at the sides of each panel in opposite directions from the plane of such 35 panel to expand the same while maintaining the central portions of the strips uniformly spaced.

16. Apparatus for expanding metal sheets having alternate unslotted strips and staggered rows of inclined slits arranged in 40 panels between unslotted strips with the slits of adjacent panels oppositely inclined, comprising feeding and forming rolls and 45 cooperating guides for engaging and maintaining the strips uniformly spaced and parallel to the original plane of the sheet and for progressively twisting the portions of the strips at the sides of each panel in opposite directions from the plane of such 50 panel to expand the same, and rolls and guides for then twisting the strips back toward the general plane of the sheet and simultaneously spreading them apart in such 55 plane.

17. Apparatus for expanding metal sheets having alternate slotted panels and unslotted strips comprising feeding and forming rolls and 60 cooperating guides for engaging the strips to continuously advance the sheet and progressively form the strips into deep ribs 65

alternately projecting in opposite directions from the general plane of the sheet and thereby expand the panels.

18. Apparatus for expanding metal sheets having inclined rows of staggered slits arranged in panels between unslotted strips with the slits of adjacent panels oppositely inclined, comprising feeding and forming rolls and cooperating guides arranged to engage the unslotted strips between the panels 70 to continuously advance the sheets and form the strips into deep ribs to thereby expand the panels while maintaining the central portions of the strips uniformly spaced.

19. Apparatus for expanding metal sheets having inclined rows of staggered slits arranged in panels between unslotted strips with the slits of adjacent panels oppositely inclined, comprising feeding and forming rolls and cooperating guides arranged to engage the unslotted strips between the panels 80 to continuously advance the sheets and form the strips into deep ribs to thereby expand the panels while maintaining the central portions of the strips uniformly spaced, and additional rolls and guides for flattening, laterally spreading and centrally beading the 85 ribbed strips.

20. Apparatus for expanding metal sheets having inclined rows of strands and staggered bonds arranged in panels between unslotted strips with the rows and adjacent 90 panels oppositely inclined, comprising cooperating rolls and guides arranged to engage the strips to continuously advance the sheet and form the strips into substantially V-shaped ribs projecting alternately in opposite directions from the general plane of the sheet to thereby expand the panels and incline the bonds and strands of each panel 95 in the same direction as the adjacent side portions of the ribs.

21. Apparatus for expanding metal sheets having inclined rows of strands and staggered bonds arranged in panels between unslotted strips with the rows and adjacent 100 panels oppositely inclined, comprising cooperating rolls and guides arranged to engage the strips to continuously advance the sheet and form the strips into substantially V-shaped ribs projecting alternately in opposite directions from the general plane of the sheet to thereby expand the panels while maintaining the same substantially in the original plane of the sheet and additional 105 rolls and deflecting guides for flattening and laterally spreading the V-shaped ribs.

22. Apparatus for expanding metal sheets that are slotted in panels to form rows of strands and staggered bonds oppositely inclined in adjacent panels and between unslotted strips, comprising feeding and forming rolls arranged to engage the marginal 115 and alternate unslotted strips of the sheets to continuously advance the same and form 120

such strips into substantially V-shaped ribs projecting in one direction from the general plane of the sheet, and cooperating forming rolls arranged to engage the other strips of the sheets and form the same into substantially V-shaped ribs projecting in opposite direction from the general plane of the sheet, said last mentioned rolls being adapted to permit a slight relative longitudinal movement of the strips engaged thereby.

23. Apparatus for expanding metal sheets that are slitted in panels to form rows of strands and staggered bonds oppositely inclined in adjacent panels and between unslitted strips, comprising feeding and forming rolls arranged to engage the marginal and alternate unslitted strips of the sheets to continuously advance the same and form such strips into substantially V-shaped ribs projecting in one direction from the general plane of the sheet, cooperating forming rolls arranged to engage the other strips of the sheets and form the same into substantially V-shaped ribs projecting in opposite direction from the general plane of the sheet, said last mentioned rolls being adapted to permit a slight relative longitudinal movement of the strips engaged thereby, and additional feeding rolls and spreading guides for flattening, laterally spreading and centrally beading the strips.

24. The method of expanding metal sheets having inclined rows of staggered slits arranged in panels between unslitted strips and forming inclined rows of strands and integral connecting bonds, which consists in drawing apart the portions of the unslitted strips at the sides of each panel by twisting such portions about longitudinal axes and in opposite directions from the plane of the panel.

25. The method of expanding metal sheets having inclined rows of staggered slits arranged in panels between unslitted strips and forming inclined rows of strands and integral connecting bonds, which consists in drawing apart the portions of the unslitted strips at the sides of each panel by twisting such portions about longitudinal axes and in opposite directions from the plane of the panel, then twisting the strips back toward the general plane of the sheet and laterally spreading the same in such plane.

26. The method of expanding metal sheets having inclined rows of staggered slits arranged in panels between unslitted strips and forming inclined rows of strands and integral connecting bonds, which consists in continuously advancing each sheet and progressively drawing apart the portions of the unslitted strips at the sides of each panel by twisting such portions about longitudinal axes.

27. The method of expanding metal sheets

having inclined rows of staggered slits arranged in panels between unslitted strips and forming inclined rows of strands and integral connecting bonds and with the rows in adjacent panels oppositely inclined, which consists in drawing apart the margins of each of the panels by forming the unslitted strips into V-shaped ribs projecting alternately in opposite directions from the general plane of the sheet.

28. The method of expanding metal sheets having inclined rows of staggered slits arranged in panels between unslitted strips and forming inclined rows of strands and integral connecting bonds and with the rows in adjacent panels oppositely inclined, which consists in drawing apart the margins of each of the panels by forming the unslitted strips into V-shaped ribs projecting alternately in opposite directions from the general plane of the sheet, then flattening and simultaneously laterally spreading the ribbed strips while maintaining the same substantially in the original plane of the sheet.

29. The method of expanding metal sheets having inclined rows of staggered slits arranged in panels between unslitted strips and forming rows of strands and integral connecting bonds with the rows in adjacent panels oppositely inclined, which consists in effecting the expansion of the slitted panels by forming the unslitted strips at the sides of each panel into deep ribs projecting in opposite directions from the plane of the panel, then flattening and laterally spreading the ribbed strips in the general plane of the sheet.

30. The method of expanding metal sheets having inclined rows of staggered slits arranged in panels between unslitted strips and forming rows of strands and integral connecting bonds with the rows of adjacent panels oppositely inclined, which consists in continuously advancing each sheet and progressively drawing the margins of each panel apart by forming the unslitted strips into deep substantially V-shaped ribs that project alternately in opposite directions from the general plane of the sheet.

31. The method of expanding metal sheets having inclined rows of staggered slits arranged in panels between unslitted strips and forming rows of strands and integral connecting bonds with the rows of adjacent panels oppositely inclined, which consists in continuously advancing each sheet and progressively drawing the margins of each panel apart by forming the unslitted strips into deep substantially V-shaped ribs that project alternately in opposite directions from the general plane of the sheet, then flattening said ribbed strips and laterally spreading the same in the general plane of the sheet.

32. Apparatus for expanding metal sheets having inclined rows of staggered slits arranged in panels between unslitted strips and forming inclined rows of strands and 5 integral connecting bonds and comprising cooperating feeding and forming rolls arranged to engage the unslitted strips between the panels to continuously advance the sheet and progressively twist the portions 10 of the strips adjacent the sides of each panel about longitudinal axes and in opposite directions from the plane of the panel, and additional sets of feeding rolls and deflecting guides for subsequently flattening 15 the strips and laterally spreading the same substantially in the original plane of the sheet.

33. Apparatus for expanding metal sheets having inclined rows of staggered slits arranged in panels between unslitted strips 20 and forming inclined rows of strands and integral connecting bonds with the rows in adjacent panels oppositely inclined, and comprising sets of feeding and forming rolls arranged to engage the unslitted strips to 25 continuously advance each sheet and progressively form the strip into deep substantially V-shaped ribs projecting alternately in opposite directions from the general plane of the sheet and additional rolls and 30 deflecting guides for flattening and laterally spreading the ribbed strips.

JAMES H. DEAN.
